UNITED STATES PATENT OFFICE.

JAN STEYNIS, OF BAY SHORE, NEW YORK, ASSIGNOR TO STEYNIS OZONE COMPANY, A CORPORATION OF NEW YORK.

APPARATUS FOR THE PRODUCTION OF OZONE.

1,085,489.

Specification of Letters Patent. Patented Aug. 13, 1912.

Application filed January 18, 1911. Serial No. 603,276.

To all whom it may concern:

Be it known that I, JAN STEYNIS, a subject of the Queen of the Netherlands, residing at Bay Shore, in the county of Suffolk, State of New York, have invented certain new and useful Improvements in Apparatus for the Production of Ozone, of which the following is a full, clear, and complete disclosure.

10 My invention relates to apparatus for the production of ozone of the kind wherein a current of air is passed through silent or streaming electrical discharges.

The object of my invention is to produce 15 an ozone-apparatus adapted to carry out the process of making ozone described in my Patent No. 906,468, which will be relatively small and compact, and which will require a minimum amount of attention and in 20 which the electrodes may be easily and quickly removed and inserted.

A further object is to so arrange and dispose the high-tension electrical conductor leading to said apparatus that there will be 25 no danger of moisture collecting at the point where the conductor enters the apparatus, and that the attendants cannot accidentally come in contact therewith.

In the drawings accompanying and forming a part of this specification, I have illustrated one embodiment of my invention.

In these drawings Figure 1 is a vertical section, and Fig. 2 is a top plan view with portions of the casing broken away, to show 30 the interior of the apparatus.

In these drawings the same reference numerals are used in both views to designate the same parts. The apparatus is provided with a heat insulating case 1, in which, near the top thereof, there is disposed an air-chamber 2. A second chamber 3 is located at the bottom of the insulating case, and the two chambers are connected by a plurality of tubes 4. I have illustrated four of these tubes, although it is obvious that the number may be varied within wide limits. Each of these tubes is provided with a cooling jacket 5 adapted to receive a cooling agent, such as ammonia gas. These jackets 35 are connected in series, as shown in Fig. 2, so that the cooling medium may enter the apparatus by the conduit 6, and after passing through all of the jackets in succession, be carried away by the conduit 7. Suitable valves may be provided in these conduits 6

and 7, in order that the cooling effect may be regulated by the attendant, and a uniform temperature maintained in the apparatus. Inside of each of the tubes 4 there is placed a dielectric tube 8 extending throughout the tube and slidably fitting therein, so that it may readily be withdrawn. Inside of these dielectric tubes there are disposed electrodes 9, in the form of elongated rods each having a series of rings 10 thereon. 60 These electrodes are supported by spiders 20, one at each end of the dielectric tubes, and the arrangement is such that the dielectric tubes and the electrodes therein may be withdrawn vertically through the observation windows 11, one of which is located above each of the tubes. The electrodes 9 at their lower ends rest on contacts 12 mounted on an insulated metallic plate 13 energized by means of the high-tension conductor 14 which extends up through the conduit 15 which is closed at its upper end by the insulator 16. The air to be ozonized enters the upper chamber 2 through the pipe 17, from which chamber it passes down 80 through the tubes 4 into the lower chamber 3 and out by way of the pipe 18. The silent discharges take place from the rings 10 on the electrodes 9 to the tubes 4, the latter constituting the other electrodes. 85

The entire apparatus is grounded, with the exception of the inner electrodes 9 and the conductor and contacts which supply the current to those parts.

In the operation of the apparatus the air, as it passes each of the rings 10, is progressively ozonized, and the heat which is imparted to the air as it passes each of these rings is immediately extracted by the cooling effect of the jackets, so that the 90 method of progressively ozonizing and cooling the treated gas step by step, described in my prior patent, is realized in the operation of this apparatus. It will be observed that a discharge pipe 18 for conducting away the treated gas, leaves the conduit 15 some distance below its upper end, so that the upper end of this conduit will contain a dead air chamber, and since the insulator 16 closes the top of the dead air 105 chamber, and the temperature of the gas or air in this chamber is not appreciably lower than that of the surrounding atmosphere, the liability of moisture collecting 110 on the insulator and grounding the high

tension conductor is excluded. The conduit 15 is extended to such a height above the apparatus as to place the high-tension conductor out of the reach of attendants, and this arrangement therefore not only prevents the accumulation of moisture and the grounding of the high-tension conductor, but serves the additional purpose of a protection for the attendants.

10 The operation of my improved apparatus may readily be understood from the foregoing description.

Air previously dried is admitted by the pipe 17 and the cooling medium by the pipe 18. The temperature of the cooling medium is so regulated that no moisture will be precipitated by the air passing through the machine. The air is progressively ozonized and cooled as described in my said patent, and leaves the machine by way of the conduit 15 and pipe 18. The operation of the electrodes may be observed through the windows 11, and in case any of the electrodes do not operate properly, such electrodes may easily and quickly be withdrawn through the windows 11 for repair or replacement by other electrodes. In order to do this, it is only necessary to draw the dielectric tubes, and the electrodes supported thereon, upwardly, there being no screws or nuts or fastenings holding these tubes in position. The parts may then be repaired or new dielectric tubes and electrodes inserted.

35 While I have described only one embodiment of my invention, I am aware that the details thereof may be varied without departing from the spirit or scope of my invention.

40 What I claim is:

1. In ozone apparatus, the combination of an elongated tube constituting one electrode, a rod concentrically disposed therein constituting the other electrode, a dielectric tube supporting the two electrodes, a series of discharge rings mounted on said rod and spaced from the dielectric, substantially as described.

2. In ozone apparatus, the combination

of an elongated tube constituting one electrode, a dielectric tube slidably mounted therein, an elongated rod supported by said dielectric tube, and a series of discharge rings on said rod spaced from said electrode, substantially as described.

3. In ozone apparatus, two oppositely disposed chambers connected by hollow electrodes, a plurality of electrical contacts in one chamber and a plurality of removable electrodes located in the hollow electrodes and extending from one chamber to the other with their ends resting on said contacts, substantially as described.

4. In an ozone apparatus, the combination of an elongated tube constituting one electrode, a dielectric tube removably supported therein, an elongated rod concentrically supported in said dielectric tube and constituting the other electrode, and an observation window in line with said electrodes through which the inner electrode and dielectric can be withdrawn and inserted, substantially as described.

5. In ozone apparatus, an elongated hollow electrode, a dielectric tube slidably supported therein, a second electrode mounted in and supported by said dielectric tube and spaced therefrom by insulators, a series of discharge rings mounted on said second electrode and spaced from said dielectric tube, substantially as described.

6. In ozone apparatus, a discharge conduit, an insulator at the end thereof, an electrical conductor extending through said tube and insulator, and a dead air pocket in said conduit at said insulator, substantially as described.

7. A combination in a machine of the kind described, of an upwardly extending grounded air conduit, an insulator located on and inclosing the upper end of said conduit, a high tension conductor extending through said conduit and insulator, substantially as described.

JAN STEYNIS.
